CLAIM

The ornamental design for a rear sight for a firearm, as shown and described.

DESCRIPTION

FIG. 1 is a front elevation view of the rear sight for a firearm in a stowed position.

FIG. 2 is a rear elevation view of the rear sight for a firearm of FIG. 1.

FIG. 3 is a left/front/top perspective view of the rear sight for a firearm of FIG. 1.

FIG. 4 is a right elevation view of the rear sight for a firearm of FIG. 1.

FIG. 5 is a left elevation view of the rear sight for a firearm of FIG. 1.

FIG. 6 is a top plan view of the rear sight for a firearm of FIG. 1.

FIG. 7 is a bottom plan view of the rear sight for a firearm of FIG. 1.

FIG. 8 is a right/top/rear perspective view of the rear sight for a firearm of FIG. 1.

FIG. 9 is a right/bottom/rear perspective view of the rear sight for a firearm of FIG. 1.

FIG. 10 is a right/bottom/front perspective view of the rear sight for a firearm of FIG. 1.

FIG. 11 is a right/top/front perspective view of the rear sight for a firearm of FIG. 1.

FIG. 12 is a left/bottom/front perspective view of the rear sight for a firearm of FIG. 1.

FIG. 13 is a left/bottom/rear perspective view of the rear sight for a firearm of FIG. 1.

FIG. 14 is a left/top/rear perspective view of the rear sight for a firearm of FIG. 1.

FIG. 15 is a front elevation view of the rear sight for a firearm in a deployed position.

FIG. 16 is a rear elevation view of the rear sight for a firearm of FIG. 15.

FIG. 17 is a left/front/top perspective view of the rear sight for a firearm of FIG. 15.

FIG. 18 is a right elevation view of the rear sight for a firearm of FIG. 15.

FIG. 19 is a left elevation view of the rear sight for a firearm of FIG. 15.

FIG. 20 is a top plan view of the rear sight for a firearm of FIG. 15.

FIG. 21 is a bottom plan view of the rear sight for a firearm of FIG. 15.

FIG. 22 is a right/top/rear perspective view of the rear sight for a firearm of FIG. 15.

FIG. 23 is a right/bottom/rear perspective view of the rear sight for a firearm of FIG. 15.

FIG. 24 is a right/bottom/front perspective view of the rear sight for a firearm of FIG. 15.

FIG. 25 is a right/top/front perspective view of the rear sight for a firearm of FIG. 15.

FIG. 26 is a left/bottom/front perspective view of the rear sight for a firearm of FIG. 15.

FIG. 27 is a left/bottom/rear perspective view of the rear sight for a firearm of FIG. 15; and,

FIG. 28 is a left/top/rear perspective view of the rear sight for a firearm of FIG. 15.
